METHOD AND MEANS FOR SECURING GOLF CLUB HEADS TO SHAFTS

John A. Hillerich, Louisville, Ky.

Application October 19, 1929. Serial No. 400,857

7 Claims. (Cl. 273—80)

The invention relates to golf club and has for a principal object to provide an improved method and means for securing iron golf club heads to hollow steel shafts.

In the assembly of golf clubs of the character described it has usually been the practice to secure the club heads to the steel shafts by boring a hole transversely through both the shaft and head after the shaft has been inserted in the cored end of the shank, and securing the parts together by the insertion of a pin through the aligned apertures. This method is subject to objections and disadvantages largely for the reason that the parts are weakened by the transverse boring operation, thereby detracting from the strength and durability of the clutch. This method is further objectionable for the reason that a solid, rigid and continuous union is not obtained, with the result that vibrations set up in the club head during use are frequently transmitted to the shaft and thence to the hands of the player with consequent sting and discomfort to the player.

An important object of the invention is to provide a more secure and permanent method of attaching the golf club head to the shaft and to effect the same in a more convenient and economical manner with the use of a minimum of parts and appliances.

A further object of the invention is to provide a fastening means of the character described which will result in a club of improved and more satisfactory balance over clubs now being manufactured and which are not perfectly balanced by reason of the present methods of securing the head to the shaft.

A still further object is to provide fastening means which will result in the elimination of vibration and attendant physical discomfort which frequently obtains from present methods of securing iron clubs to steel shafts as commonly employed.

With such objects in view, as well as other advantages which may be incident to the use of the improvements, the invention consists in the parts and combinations thereof hereinafter set forth and claimed, with the understanding that the several necessary elements constituting the same may be varied in proportions and arrangement without departing from the nature and scope of the invention.

In order to make the invention more clearly understood there are shown in the accompanying drawings means for carrying the same into practical effect, without limiting the improve-

ments, in their useful applications, to the particular constructions which, for the purpose of explanation, have been made the subject of illustration.

In said drawing,

Fig. 1 is a vertical sectional view, partially in elevation, showing an iron golf club head and lower portion of the steel shaft in assembled position prior to completing the fastening and permanent union of the parts.

Fig. 2 is a similar view showing the relation of the parts after the fastening or securing operation has been completed and the fastening member driven home.

Fig. 3 is an enlarged transverse section on line 3—3 of Fig. 1.

Fig. 4 is a similar view on line 4—4 of Fig. 2, the configuration of the parts being slightly exaggerated for clearness.

Fig. 5 is an enlarged perspective view of the fastening member.

Referring to the drawing, 1 indicates the iron golf club head having an upwardly projecting preferably integral shank or hosel 2 provided with a central tapered socket or bore 3. The golf club shaft is shown at 4 and consists of a hollow rolled steel tubing of known construction open at its upper and lower ends and preferably tapered or reduced from top to bottom as is usual in steel shafts of the character to which the present invention appertains. The fastening member is shown at 5 and consists preferably of a solid cylindrical member of hardened or tempered steel and which is slightly tapered from top to bottom to conform to the tapered inner cylindrical wall of the hollow steel shaft within which the fastening member is designed to be inserted and thereafter secured. The hardened steel cylindrical member 5 is provided along its surface with projections which may be in the form of one or more series of longitudinally or vertically aligned outwardly projecting teeth 6 integral with the cylinder and which teeth are preferably formed by notching or serrating the cylinder prior to the hardening or tempering operation.

In assembling the parts the lower end of the hollow shaft 4 is inserted into the bore or socket 3 of the shank or hosel 2 of the iron head. The socket 3 is tapered to conform to the taper of the hollow shaft and a wedging engagement is thereby obtained. The tapered steel fastening member or cylinder 5 is then inserted into the upper end of the hollow steel shaft, with its reduced end lowermost and upon being released

will drop into the position shown in Fig. 1. This initial position of the cylinder is determined by its cross-sectional dimensions when manufactured as will be obvious. A suitable rod or other driving implement, indicated at 7, is next inserted downwardly through the open upper end of the shaft by means of which rod the cylindrical member is forcibly driven downwardly into final locking position as shown in Fig. 2. This driving force and downward movement of the cylinder serves to firmly engage the aligned series of hardened teeth or lugs 6 with the softer metal of the hollow steel shaft on the inner surface thereof. The parts are thereby locked against relative movement and subsequent displacement by reason of the interengagement of the teeth 6 formed by the notches, with the metal of the shaft. This biting engagement is best seen in Fig. 4. It is to be further understood that when the cylinder 5 is driven downwardly the lower end of the hollow shaft is thereby expanded outwardly into firm locking engagement with the walls of the socket 3 of the club head shank, thereby obtaining a secure and permanent union of the parts which union extends for a considerable area. After the described locking engagement is effected and obtained, the rod 7 is of course removed and the open upper end of the hollow shaft is closed and finished or provided with a ferrule or cap in the usual and accepted manner.

The member 5 has been illustrated as provided with four longitudinally aligned series of teeth or lugs 6 suitably spaced at an angle of 35. 90° apart about is circumference, but it will be understood that any desired number of such series may be employed or the described teeth may be arranged in staggered relation if desired. The engagement of the teeth with the softer 40. relatively thin walls of the shaft serves to force or extrude the latter outwardly perceptibly at the points where this engagement occurs. This action is best shown in Fig. 4 and results in correspondingly extruding or bulging outwardly 45. at these points the relatively softer metal of the iron shaft or hosel 2. This results in a tight locking engagement of the shaft with the shank so that relative rotation and vertical displacement of the parts is effectually prevented. The lateral bulging or extrusion of the parts by reason of the driving engagement of the tempered steel teeth of the cylinder, and which has been slightly exaggerated for clearness in Fig. 4 of the drawing, is of course limited to the vertical area 50. of engagement of the cylinder with the shaft thereby aiding in preventing longitudinal displacement of the parts.

It will be apparent from the foregoing that a simple and economical method has been provided effecting a firm and permanent union of the iron club head with the hollow steel shaft, only a single locking member is required, and the parts are not weakened by drill holes incident to known and present forms heretofore practiced for securing the iron club head to the shaft. It will be further apparent that the invention may be practiced to economical advantage and is not attended by loss and displacement of fastening devices, such as screws, rivet pins and the like. The fastening obtained by the present invention results in a union which is semi-solid and extended over a considerable area, thereby providing a complete golf club of unitary character and which is not subject to transmitted vibrations from the head to the shaft

with attendant sting or physical discomfort to the hands of the user as described.

The fastening means contemplated and obtained by the present invention provides a golf club of better and improved balance for the reason that the weight which has been heretofore ground or removed from the shanks of the iron club heads in order to reduce them to a size proportionate to the size of the shafts, is returned to the shank or hosel in the form of the weight of the steel cylinder 5, thereby obtaining and resulting in a better balance of the head part of the club. The engagement of the notches with the side walls of the steel shaft after the cylinder 5 has been driven home effectually prevents and insures against any tendency of the parts to twist or turn relative to one another when the club is in use.

The provision of the pin or fastening member 5 further serves to materially strengthen the hollow shaft of the assembled golf club and serves to stiffen the same against shocks and stresses. This greatly minimizes the possibility of breaking the shaft during use, particularly at its point of union with the club head where a considerable portion of the playing strain is received by the club.

What is claimed is:

1. Means for attaching the shanks of iron golf club heads to hollow tapered steel shafts comprising a substantially cylindrical solid metal member tapered to conform to the internal taper of said shaft and insertable therein, said member being adapted to be driven into wedging engagement with the inner wall of said shaft and having projections thereon for biting into and expanding outwardly the metal of said shaft into firm wedging and locking engagement with the metal of the said shank, whereby vertical and rotary relative movement of said head and shaft are prevented.

2. In a golf club, the combination of a head having a tubular shank, a tapered tubular shaft entering said shank, and a tapered plug forced into and within said shaft and located also within said shank at substantially the outer end of the shank, said tapered plug having means extending outwardly from its tapered surface for extruding outwardly the metal of said shaft into frictional engagement with said shank to secure the shaft to the shank and also to strengthen the shaft at a point subjected to great strain.

3. In a golf club the combination of a hollow metal shaft and a metal head, the shaft being tapered exteriorly and interiorly to a point within the head, the head having a socket tapered to correspond with the taper of the lower end of the shaft, a drive-plug tapered in the same direction as the shaft and corresponding in taper with the interior of the lower end of the shaft, and outward projections on said drive plug adapted to engage and extrude outwardly the metal of the shaft into firm locking engagement with said head, whereby the lower end of the shaft is secured to the head by said plug after the latter has been inserted and driven into place through the upper end of said hollow shaft.

4. In a golf club the combination of a head having a shank provided with a socket, a hollow shaft insertable in said socket, a tapered member insertable in said shaft to a point within the confines of said socket, and means on said member and in addition to the taper thereof for engaging the inner surface of said shaft and extruding outwardly a portion of said shaft into

locking engagement with said socket for preventing the displacement of said shank relative to said shaft.

5. In a golf club, the combination of a head having a metal shank provided with a socket, a substantially cylindrical member insertable in said shaft to a point within the confines of said socket and adapted to be driven into wedging engagement with the inner wall of said shaft, 10 said member having an outward projection thereon for biting into and expanding outwardly the metal of said shaft into firm wedging and locking engagement with the metal of said shank, whereby relative vertical and rotary movement 15 of the head and shaft are prevented.

6. A golf club, comprising in combination: a head having a socket open at the upper end only, a hollow shaft and a plug disposed within

the hollow shaft and insertable with said shaft through the open end of said socket, said plug being provided with laterally extending means contoured to expand said shaft into interlocking engagement with the wall of said socket and with said plug when the plug is driven downwardly into said socket.

7. A golf club, comprising a head having a shank provided with a bore, a hollow shaft, and a plug disposed within the hollow shaft and insertable with said shaft into the upper end of said bore, and laterally extending means on said plug for extruding said shaft into interlocking engagement with the wall of said bore at a point above the lower end of said shaft when the plug is driven downwardly into said bore.
